His Attorney.

UNITED STATES PATENT OFFICE

2,588,934

WAVE GUIDE SWITCH

Charles W. Miller, Sale, England, assignor to
General Electric Company, a corporation of
New York

Application January 7, 1948, Serial No. 965
In Great Britain August 21, 1946

6 Claims. (Cl. 178—44)

1

My invention relates to a wave guide structure for guiding waves for ultra high frequency and, more particularly, to a selective connection for a wave guide junction.

It is sometimes desirable to have a means of switching the path of guided waves such as where duplicate radar equipment is used and where a common antenna may be connected to either equipment.

It is an object of my invention to provide a two-way selective connection for a T wave guide junction.

A further object of my invention is to provide means for deflecting waves in one direction at a wave guide junction and for preventing their flow in the opposite direction.

Another object of my invention is to provide switching means for controlling the paths of guided waves.

For additional objects and advantages, and for a better understanding of the invention, attention is now directed to the following description and accompanying drawing, and also to the appended claims in which the novel features of the invention are particularly pointed out. In the drawing:

Fig. 1 is a vertical cross-section of a T wave junction in which my invention is embodied;

Fig. 2 is a vertical cross-section of a T wave guide junction showing another embodiment of my invention;

Fig. 3 is an end view of the structure as shown in Fig. 2; and

Fig. 4 is a top view of the structure as shown in Fig. 2.

In Fig. 1 the main arm of the T wave guide junction is indicated by the symbol Y. The branches of the cross-arm are indicated by the symbols X₁ and X₂. According to my invention a selective connection is provided between the main arm Y and the two branches X₁ and X₂ by means of a sliding block 1. The position of block 1 as shown in Fig. 1 is such as to provide communication between the wave guides Y and X₂ with the wave guide X₁ being cut off. When moved to the alternate position, as shown by the dotted lines in Fig. 1, communication is effected between the wave guides X₁ and Y and the wave guide X₂ is cut off. The block 1 is formed with pairs of conducting surfaces 2 and 4. In the embodiment shown, the member 1 is made symmetrical and hence the opposing surfaces 2 and 4 have both been accorded the same reference numerals. It will be observed that block 1

2

is of substantially inverted triangular form with an extension 3 of rectangular cross-section at the apex of the triangle. In the position illustrated, one wall 4 of the apex portion 3 constitutes an extension of the adjacent wall of the main wave guide member Y, while the connecting oblique surface 2 serves to deflect waves passing between the wave guide Y and the wave guide X₂, or vice versa, without causing reflection. The distance between the surface 2 and the inner corner of the wave guide X₂ and Y, which in the drawing is indicated by the letter d, is suitably chosen according to the frequency of the waves to be transmitted.

The block 1 is slidable between the two positions, the alternate position being indicated in dashed outline in Fig. 1. The upper face is machined out as shown at 5, leaving two contact portions 6 which abut against the upper walls of the cross-member X₁ and X₂. By restricting the abutting portions to the surface provided by the portions 6, satisfactory contact can be obtained. In order to seal the unused branch, the length of the lower side, that is, the width of the rectangular apex portion 3, is made equal to one-quarter wave length at the frequency of the signal to be transmitted.

In the modification as shown in Fig. 2, the sealing of the upper surface of the block 1 is effected by extension pieces 7. Care must be taken that the ends of these extension pieces 7 do not cause reflections. In order to actuate the block 1, an actuating block 8 is attached to it by screws 9 or any other suitable means. The screws 9 pass through a slot 10 in the upper wall of the wave guide X₁ and X₂. A spring 11 is interposed between the actuating block 8 and the upper wall of the wave guide so as to provide a degree of friction to retain it in position. The extension 12 also serves to cover the slot 10 so as to render the upper wall of the wave guide continuous for all positions of the block 1. Movement of the block 1 is limited by adjustable stops 12 located at either end of the position of travel. Actuation may be effected by any suitable toggle mechanism such as an actuating arm 13.

While this arrangement is primarily designed for a T wave guide junction lying in the H plane, a similar arrangement may be used for a T wave guide junction lying in the E plane. The arrangement shown may be used in rectangular wave guides propagating H₀₁ or TE₀₁ modes.

It will now be appreciated that block 1 is slidable along the cross-member of the T between operative positions in each of which it respec-

tively blocks one of the cross-arms and provides connection between the alternative arm and the main member of the T. This block is formed with deflecting surfaces, one of which in each operative position lies across the outer corner of the passage between the interconnected members so as to deflect waves around the corner without causing appreciable deflection.

While certain specific embodiments have been shown and described, it will, of course, be understood that various modifications may be made without departing from the invention. The appended claims are, therefore, intended to cover any such modifications within the true spirit and scope of the invention.

What I claim as new and desire to secure by Letters Patent of the United States is:

1. In a wave guide structure, a main arm, a pair of branch cross arms, a metallic electromagnetic wave deflecting member slidable along said branch cross arms between alternate operative positions in each of which said deflecting member blocks electromagnetic wave transmission through one of said cross arms and provides electromagnetic wave communication between the other arm and said main arm, said deflecting member being formed with deflecting surfaces, one of which in each of said operative positions lies across the outer corner of the angle passage between said interconnected arms.

2. A T-shaped wave guide structure comprising, in combination, a main arm intersecting a pair of axially aligned transverse arms, selective switching means for selectively connecting said arm with one of said transverse arms for energy transfer therebetween while blocking transfer of energy between said main arm and the other transverse arm, said means comprising an electromagnetic wave reflecting member movable within said transverse arms from one side of said junction to the other, said member being in conductive engagement with the wall of said transverse arms opposite said junction and having a free end in close proximity to the opposite wall in either of said positions.

3. A T-shaped wave guide structure comprising, in combination, a main arm intersecting a pair of axially aligned transverse arms, selective switching means for connecting said main arm with only one of said transverse arms at a time for energy transfer therebetween, said means comprising an electrically reflecting block member conductively supported within said transverse arms and selectively movable to either of two positions on opposite sides of the junction with said main arm, said member being shaped to define in either position an extension of the adjacent wall of said main arm for a portion of the distance across said transverse arms and an angularly disposed flat reflecting surface for the remaining portion of said distance.

4. In a T-shaped wave guide structure for operation at a predetermined frequency comprising,

ing, in combination, a main arm intersecting a pair of axially aligned transverse arms, selective switching means for connecting said main arm with either one of said transverse arms for energy transfer therebetween while blocking energy transfer between said main arm and the other of said transverse arms, said means comprising an electrically reflecting block member movable within said transverse arms to either, of two operating positions one on each side of said junction, said member being in conductive engagement with the wall of said transverse arms opposite said junction and having a free end in close proximity to the opposite wall in either of said positions, said member having a thickness at its free end as measured axially along the unused transverse arms substantially a $\frac{1}{4}$ wave length at the predetermined operating frequency.

5. In a wave guide structure for operation at high frequency, a pair of axially aligned arms, a second arm intersecting said axially aligned arms at a common junction point and lying substantially perpendicular to the longitudinal axis of said axially aligned arms, a switching member movable within said first arms between two alternate operating positions, said member defining a passage for electromagnetic waves between one of said aligned arms and said second arm in either position and simultaneously blocking communication of electromagnetic waves between said second arm and the other of said aligned arms.

6. A T-shaped wave guide structure comprising, in combination, a main arm intersecting a pair of axially aligned transverse arms, selective switching means for connecting said main arm with either one of said transverse arms for energy transfer therebetween while blocking transfer of energy between said main arm and the other of said transverse arms, said means comprising a movable member conductively supported within said transverse arms and having a pair of reflecting surfaces spaced along the axis of said transverse arms and angularly disposed to one another, an operating member extending through a slot in a wall of said transverse arms and secured to said movable member for positioning each of said surfaces with respect to said main arm and a respective one of said transverse arms for reflecting energy between said main arm and said respective transverse arms.
